[57] CLAIM

The ornamental design for a container for sausage-shaped articles, as shown and described.

DESCRIPTION

FIG. 1 is a perspective view of a container for sausage-shaped articles showing my new design in an open position,

FIG. 2 is a bottom plan view thereof;

FIG. 3 is a side elevational view thereof;

FIG. 4 is a cross-sectional view taken along line 4—4 of FIG. 1;

FIG. 5 is a left end elevational view of FIG. 3; and

FIG. 6 is a perspective view of the container in the closed position.

FIG. 3.

FIG. 4.

FIG. 5.
